[57] **CLAIM**

The ornamental design for a diskette storage container for holding a plurality of diskettes, substantially as shown and described.

DESCRIPTION

FIG. 1 is a perspective view of a diskette storage container for holding a plurality of diskettes showing our new design in closed condition;

FIG. 2 is a perspective view thereof in open condition;

FIG. 3 is a front elevational view of FIG. 1;

FIG. 4 is a left side elevational view, the right side being

a mirror image thereof;

FIG. 5 is a top plan view thereof;

FIG. 6 is a bottom plan view thereof; and

FIG. 7 is a rear elevational view thereof.
